[57] CLAIM

The ornamental design for pair of fabric handcuffs, as shown and described.

DESCRIPTION

FIG. 1 is a perspective view of a pair of fabric handcuffs showing my new design;

FIG. 2 is a front elevational view thereof;

FIG. 3 is a top plan view thereof;

FIG. 4 is an end elevational view thereof;

FIG. 5 is a rear elevational view thereof; and,

FIG. 6 is a bottom plan view thereof.

The crosshatched shading shown in FIGS. 1-6 is understood to repeat throughout the indicated area. The broken lines in FIGS. 1,3,4, and 6 are understood to represent conventional stitching.
